UNITED STATES PATENT OFFICE.

GEORGE E. FEAGANS, OF LOS ANGELES, CALIFORNIA.

DESIGN FOR A BUTTON.

59,206.

Specification for Design.

Patented Oct. 4, 1921.

Application filed November 1, 1920. Serial No. 421,178. Term of patent 14 years.

To all whom it may concern:

Be it known that I, GEORGE E. FEAGANS, a citizen of the United States, residing at Los Angeles, in the county of Los Angeles and State of California, have invented a new, original, and ornamental Design for Buttons, of which the following is a specification, reference being had to the accompanying drawing, forming a part thereof.

In this drawing,

Figure 1 is a front elevation of a button embodying my invention, and,

Fig. 2 is a side view thereof.

In the embodiment shown in the drawing,

a central shield is situated upon a spherical background which is surrounded by a rim having lettering thereon as follows: G. F. W. C. Unity in Diversity. Various portions of the design are colored as shown by cross hatching.

I claim as my invention:

The ornamental design for a button as shown.

GEORGE E. FEAGANS.
